UNITED STATES PATENT OFFICE.

STEPHEN KOSTSZEWSKI, OF NEW YORK, N. Y., ASSIGNOR TO ROBERT FINDLAY MANUFACTURING CO., OF NEW YORK, N. Y., A CORPORATION OF NEW YORK.

DESIGN FOR A SPINDLE FOR LIGHTING-FIXTURES.

56,174.

Specification for Design. Patented Aug. 24, 1920.

Application filed April 9, 1920. Serial No. 372,671. Term of patent 7 years.

To all whom it may concern:

Be it known that I, STEPHEN KOSTSZEWSKI, a citizen of the United States, residing at New York, in the county of New York and State of New York, have invented a new, original and ornamental Design for a Spindle for Lighting-Fixtures, of which the following is a specification, reference being had to the accompanying drawing, forming part thereof.

The figure is perspective view of a spindle for lighting fixtures, showing my new design.

I claim

The ornamental design for a spindle for lighting fixtures, as shown.

STEPHEN KOSTSZEWSKI.
